UNITED STATES PATENT OFFICE.

WILLIAM S. HADAWAY, JR., OF NEW ROCHELLE, NEW YORK.

ELECTRIC LAUNDRY-ROLL.

1,156,223.

Specification of Letters Patent.

Patented Oct. 12, 1915.

Application filed March 9, 1914. Serial No. 823,371.

To all whom it may concern:

Be it known that I, WILLIAM S. HADAWAY, Jr., a citizen of the United States of America, and a resident of New Rochelle, Westchester county, and State of New York, have invented certain new and useful Improvements in Electric Laundry-Rolls, of which the following is a specification, reference being had to the accompanying drawings, forming a part thereof.

My invention relates to electric heaters, and particularly to such as are adapted for imparting heat to a laundry roll or similar device.

In my copending application Serial No. 791,935 filed September 26, 1913, I have shown and described a laundry roll and a heater therefor of the same general character as that of my present invention.

One object of my invention is to provide a light, durable and inexpensive heater of the character above indicated, and suitable means for supporting it within a hollow, cylindrical laundry roll.

Another object is to provide a heater structure embodying bus-bars which also have the function of truss-rods and a plurality of detachable and interchangeable radiant heater units, such as are adapted for use in heaters of various different sizes and types and are not necessarily peculiar to the laundry roll heater of which they may form parts.

Other objects and advantages of my invention will be set forth hereinafter, and in order that my invention may be thoroughly understood, I will describe the same in the following specification and then point out the novel features thereof in appended claims.

Referring to the drawings: Figure 1 is an elevation in longitudinal section, of a laundry roll and heater arranged and constructed in accordance with my invention. An end elevation of the same device, with the end cap removed, is shown in Fig. 2. Figs. 3 and 4 are transverse sectional elevations, taken respectively on the lines 3-3 and 4-4 of Fig. 1. A diagrammatic view of the circuit connections of the heater is shown in Fig. 5. Fig. 6 is a view corresponding to Fig. 1, of a modified laundry roll heater structure, applied to a slightly different type of machine.

The structure shown in Figs. 1 to 4 inclusive, to which special reference may now

be had, comprises a relatively long, hollow cylindrical laundry roll 10 which forms a part of a laundry machine (not shown), and is adapted to be rotated; and a relatively stationary electric heater which extends into the roll from its outer end and is adapted to impart heat thereto.

The heater is supported in any suitable manner; and it comprises in general an end bracket 15, and end ring 20 secured thereto, a central rod 25, spaced disks 30, combined truss-rods and bus-bars 35, and a plurality of heater units 40.

The end ring 20 has lugs 20^A and a flange 21 which fits loosely into an annular projection 16 of the stationary bracket. The bracket has correspondingly located lugs 15^A through which adjusting and clamping screws extend. The rod 25 is screwed into a hub 22 of the end ring and projects therefrom as shown in Fig. 1. A wiper ring 16^A of asbestos board or like material, is secured to the end of the roll 10 and is fitted over the cylindrical surface of the annular flange 16 of the bracket. By this means the heat from within the roll is not permitted to escape by convection and the efficiency of the device is thus improved.

The disks 30 are preferably formed of sheet metal and are mounted on the rod 25. They are spaced apart and clamped in position on the rod by means of spacing and clamping sleeves 26, and a nut 27 which is screwed onto the end of the rod and presses the sleeve sections together.

The disk 30 which is secured nearer the outer end of the rod 25, is shown in Fig. 1 as provided with single contact sockets 31, each of which is adapted to receive a contact plug 95 forming a part of the heater unit 40. The other disk is shown as provided with double sockets 32 which will be described in detail hereinafter and each of which is adapted to support two units extending outwardly in opposite directions from the disk. The sectional view of the heater which forms a part of Fig. 1, is included as best adapted to illustrate the invention although as will shortly appear the disks and their attached parts are similar to each other. By reference to Fig. 3, it is evident that there are eight sockets on the side of the disk, adjacent to the end of the roll, whereas as shown in Fig. 4 there are four sockets on the side of the disk adjacent to the center of the roll.

As indicated in the diagram of Fig. 5,

there are four double sockets and four single sockets on each disk, and consequently when a heater unit is mounted in each of its sockets, eight units extend from each disk toward the adjacent end of the roll, while four units extend from each disk toward the center of the roll. The sockets are uniformly spaced on the disks and they are so placed relative to each other and to the shaft 25 that a staggered relation exists between the eight units in the center of the roll.

The number of units is of course immaterial to my invention and any suitable combination may be employed.

15 The bus-bars 35 serve not only as electrical conductors but also serve as truss-rods or supports to reinforce the central rod 25 and stiffen the heater. The bus-bars are composed of sections 35^A and 35^B. Each of 20 the sections 35^A extends through a hole in the end ring 20 and is provided with terminal binding nuts 36. It is insulated from the disk in a well known manner, by insulating washers 37 and an insulating sleeve 38. A 25 clamping nut 39 co-operates with one of the binding nuts 36 to establish a rigid mechanical connection between the disk and the bus-bars. Each of the disks 30 is perforated and metal bushings 41 extend through the 30 holes and are mechanically secured to the disks by clamping nuts 42. Nevertheless they are electrically insulated from it by washers and bushings 33 of insulating material.

35 The bus-bar sections are interconnected and mechanically united by being screwed into the respective ends of the bushings 41 on one of the disks, the free ends of the sections 35^B being screwed into the bushings on 40 the other disk. As clearly shown on the diagram of Fig. 5, the circuit connections for the several units are all established through the bus-bars and circuit conductors are merely led into the hollow bracket 15, which 45 is closed by the removable cap 16, and attached to the ends of the bus-bars by means of the binding nuts 36.

The bushings 41 are sufficiently long to support binding nuts 34 which co-operate 50 with the clamping nuts 42 to provide a ready means for establishing a circuit connection from a bus-bar to one or more of the units; for example, the connectors 34^A and 34^B are arranged as clearly shown in Figs. 3 and 4 55 with disks or washers 34^C of conducting material which are clamped to the bushing as above indicated, and contact members 34^E which are attached to the sockets.

Each of the single sockets corresponds 60 substantially to that shown in a copending application serial No. 791,936 filed September 26, 1913, by Josef Amon and myself and need not be described in detail. Each of the double socket structures comprises two apertured sockets 50, terminals 51 and 52, insu-

lating washers separating one of the terminals from the two sockets and a single central rivet 53 for securing the second terminal in contact with one of the sockets and clamping the insulating washers in position, 70 said central rivet constituting an independent circuit contact within each socket.

The heater units 40 are each provided with a plug 40^A which is adapted to co-operate with one of the sockets and may otherwise be constructed in any suitable manner. I prefer however, to utilize a structure similar to that shown and described in my copending application Serial No. 791,931, filed September 26, 1913. 80

The circuit connections may obviously be varied to adapt the heater for use on circuits of unlike voltages and since the circuit connections in themselves form no part of my present invention, a detailed description is 85 superfluous.

Where the laundry roll is relatively short the heater shown in Fig. 6 may be employed. This comprises a single disk 60 to which is secured a plurality of sockets 61, a heater 90 unit 40 being removably secured in each socket and extending into the roll from one end. This structure is well adapted for use with collar and cuff rolls which have their outer ends closed. 65 designates a roll of 95 this character and is supported by a central shaft 66 which extends beyond the inner end of the roll and is supported in a laundry machine bearing 67, the disk 60 being apertured to permit the shaft to extend 100 through it.

The disk is supported by an annular flange 63 of a stationary end bracket 64 which is hollow to constitute a terminal box and is secured to a pipe connection 68 or other projection from the laundry machine frame. 105

A padded pressure roll such as, for example, the roll 69 of Fig. 6, is arranged to co-operate with the cylindrical surface of the roll. 110

Structural variations may be effected within the spirit and scope of my invention, and I intend that only such limitations be imposed as are indicated in the appended claims. 115

What I claim is:

1. A laundry roll heater comprising a central supporting rod, sheet metal disks secured to the rod and spaced apart thereon, a plurality of combined truss-rods and bus-bars uniformly spaced about the central rod, each connected to and electrically insulated from the disks, a plurality of contact sockets secured to the disks and extending in parallelism with the bus-bars, and heating units 120 having contact plugs removably mounted in the sockets. ABC

2. A laundry roll heater comprising a plurality of substantially parallel bus-bars, means near one end for supporting the bus- 125 130

bars, spaced disks secured to and supported by the bus-bars but electrically separated therefrom, contact sockets mounted near the periphery of the disk, and heating units having contact plugs coöperating with the sockets.

3. A laundry roll heater comprising a plurality of substantially parallel bus-bars, a disk secured at right angles to the bus-bars and electrically insulated therefrom, and a plurality of contact sockets secured near the periphery of the disk and extending in parallelism with the bus-bars, said bus-bars constituting truss-rods for the heater.

15 4. A laundry roll heater comprising a plurality of substantially parallel bus-bars, a sheet metal disk secured to the bus-bars and electrically insulated therefrom, a pair of contact sockets mounted near the periphery of the disk on opposite sides thereof and comprising a single central fastening means extending through the disk and constituting an independent contact within each of the sockets.

20 5. A heater comprising a plurality of bus bars, means for supporting the bus bars, spaced members secured to and supported by

the bus bars but electrically separated therefrom, and electric heating units removably secured to the members and electrically connected to the bus bars.

5 6. A laundry roll heater comprising a plurality of substantially parallel bus bars, means near one end for supporting the bus bars, spaced disks secured to and supported by the bus bars but electrically separated therefrom, and electric heating units removably secured to the disks.

10 7. A laundry roll heater comprising a plurality of substantially parallel bus bars, means near one end for supporting the bus bars, spaced disks secured to and supported by the bus bars but electrically separated therefrom, contact sockets mounted near the periphery of the disks, and electric heating units removably mounted in the sockets.

15 In witness whereof, I have hereunto set my hand in the presence of two subscribing witnesses, this 5th day of March, 1914.

WILLIAM S. HADAWAY, JR.
